UNITED STATES PATENT OFFICE.

CHARLES L. SMITH, OF BROOKLYN, NEW YORK.

DESIGN FOR A METAL HEEL.

SPECIFICATION forming part of Design No. 25,995, dated September 8, 1896.

Application filed May 11, 1896. Serial No. 591,171. Term of patent 7 years.

To all whom it may concern:

Be it known that I, CHARLES L. SMITH, of Brooklyn, in the county of Kings and State of New York, have invented a new and useful Design for Metal Heels, of which the following is a specification.

This invention is a new and useful design for metal heels, and the essential features reside in the lugs or ears at each side of the heel, and also in the formation of the bottom of the heel.

In the drawings hereto annexed and forming a part of this specification, Figure 1 is a perspective view of the heel. Fig. 2 is a bottom plan view.

By referring to these drawings it will be seen that at each side of heel is an upwardly-projecting lug or ear A, and in the bottom of heel is a multifoil opening B. The body of heel is also curved inwardly, as at C, and

the front face is also curved, as shown at D. It will thus be seen that I provide a design for a heel which is novel, useful, and attractive or ornamental.

Having thus described my invention, what I claim, and desire to secure, is—

The design for a boot or shoe heel, having the body of heel curved inwardly, the front face of said body being also so curved, and the multifoil formation of the bottom of the heel, and the lugs or ears situated on each side of said heel, substantially as shown and described.

In testimony whereof I affix my signature in the presence of two witnesses.

CHARLES L. SMITH.

In presence of—

C. P. BARKER,
ROSE FORSYTH.
